UNITED STATES PATENT OFFICE.

WILLIAM A. SEXTON, OF NEWTON, MASSACHUSETTS.

INTERNAL-PROTECTED SHEET-METAL RECEPTACLE.

1,161,164.

Specification of Letters Patent. Patented Nov. 23, 1915.

Application filed December 26, 1914. Serial No. 879,177.

To all whom it may concern:

Be it known that I, WILLIAM A. SEXTON, a citizen of the United States, and resident of Newton, in the county of Middlesex and State of Massachusetts, have invented certain new and useful Improvements in Internally-Protected Sheet-Metal Receptacles, of which the following is a specification.

This invention relates chiefly to metal receptacles or cans made of tin plate or other metallic sheet material, tin plate being sheet iron coated with tin.

It is a well-known fact that sheet metal receptacles or cans, if used for containing certain materials, such as liquid shellac, discolor the contained material.

It is also well known that a protective layer of material which is insoluble by the alcohol in liquid shellac, and is capable of resisting the action thereof will not adhere to a metal surface, so that a sheet metal can cannot be protected by applying a protective layer, such as that hereinafter described, which is insoluble by alcohol, directly to its internal surface. It is therefore customary to store material such as shellac in non-metallic vessels of earthenware or glass, such vessels being objectionable on account of their frangibility, cost and weight.

I have discovered that a sheet metal receptacle, adapted to hold liquid shellac and other like material without discoloring the same, can be produced by cementing a non-metallic sheet material, such as paper, to the inner surface of the metal, such non-metallic material being adapted to adhere closely to metal surfaces, and then applying to the non-metallic lining thus formed a protective coating which is adapted to resist the action of shellac and other materials liable to discoloration by contact with tin or other metal, said protective coating adhering inherently to the non-metallic lining.

My invention consists in the improved internally protected sheet metal receptacle hereinafter described and claimed.

Of the accompanying drawings forming a part of this specification: Figure 1 represents a perspective view of a sheet metal plate of indeterminate area coated on one side with non-metallic sheet material and adapted to be cut up into blanks forming the members of a sheet metal receptacle or can; Fig. 2 represents a vertical section of

a sheet metal can made from the laminated sheet shown by Fig. 1; Fig. 3 is a sectional view showing portions of the three can members before they are united; Fig. 4 is an enlargement of a portion of Fig. 2, showing the protective coating hereinafter described.

The same reference characters indicate the same or similar parts in all the views.

In carrying out my invention I prefer to proceed as follows: Taking a sheet *a* of ordinary tin plate, or other metallic sheet material, I cement to one side of the same a non-metallic lining layer *b*, preferably of paper. I have used for the layer *b* the so-called Kraft paper, but I do not limit myself thereto. I find that paper may be permanently united to a metal surface by various kinds of paste, glue or cement. The lining layer *b* entirely covers one side of the metallic layer *a*. I next cut up the laminated sheet constructed as above described, to form blanks for the members of a sheet metal can, the form of the members depending on the form of the can. I have indicated by dotted lines in Fig. 1 the lines along which the laminated sheet may be cut. It will be seen that each member cut from the metal sheet is wholly covered on one side by non-metallic sheet material.

Fig. 2 illustrates a can formed by assembling members cut from the laminated sheet, 12 representing the body, 13 the bottom, and 14 the top or head of the can, there being at least three members, and the form of both ends of the can being determined by the joints which unite said members.

The members cut from the laminated sheet are formed and united in accordance with the ordinary practice of making sheet metal cans, said members being preferably united by seamed joints 15, and each member and its lining layer being handled as one piece or part during the operation of assembling the members. The non-metallic lining layers of the can members, being co-extensive with the inner sides of said members, extend through the joints and pack the latter, as shown by Figs. 2 and 4, the material of the non-metallic layers being compressible, and compressed by the joint forming portions of the can members, and therefore contributing to the tightness of the joints.

A can constructed as thus far described may be used for various purposes without

the protective coating hereinafter described, but said protective coating is essential for cans intended to contain materials liable to discoloration by contact with metal and capable of seeping through the non-metallic lining layers.

To complete the internal protection of the can, I apply to the non-metallic lining layers a protective coating in fluid form 10 adapted to inherently adhere to the non-metallic layer. When the can is to be protected against the action of material such as liquid shellac, I use with satisfactory results a protective coating composed of linseed oil varnish, this being material which is largely used for insulating purposes.

The material of the protective coating is partially absorbed by the non-metallic lining layer and, when baked or air dried, forms 20 a surface film thereon. In Fig. 4 the protective coating is shown in solid black, and is designated by the reference letter *c*.

It should be borne in mind that while the described coating will not adhere satisfactorily to a metal surface and is liable to flake or peel therefrom, it is firmly maintained by the non-metallic lining layer *b* in the form of a continuous protective layer covering all parts of the inner surface of 30 the can and entering the crevices adjacent to the joints 15. Owing to the fact that a part of the material of the protective layer is absorbed, as above stated, by the lining layer, the protective layer may be said to be 35 reinforced by the lining layer, and prevented from cracking as well as from peeling or flaking off.

I have found that a sheet metal can protected as described is capable of holding 40 shellac for a long period without the slightest discoloration.

My invention is not limited to the materials herein described for the lining layer and the protective coating. Neither is my 45 invention limited to the protection of tin plate in the manner described, it being obvious that other varieties of sheet metal may be similarly protected.

As above intimated, the sheet metal may 50 be protected and its joints packed only by the non-metallic lining, the protective coating being omitted when the can is intended to hold materials which will not be discolored by contact with the metallic surfaces due to seepage through the non-metallic lining.

I am aware that it has been proposed to 55 coat the interior of a sheet metal can with asphaltum cement composed of asphaltum dissolved in a suitable solvent. While as-

phaltum cement may adhere firmly to sheet metal, it is soluble in alcohol, and is therefore incapable of protecting the metal against liquid shellac, the fact being that a coating of asphaltum cement would be 65 speedily dissolved by the alcohol contained in liquid shellac, so that the shellac would be discolored not only by contact with the sheet metal, but also by the dissolved cement.

I have found that a coating of material 70 such as linseed oil varnish, which is insoluble in alcohol, will not adhere to sheet metal and will adhere to paper, which in turn is adapted to be firmly cemented to sheet metal.

Having described my invention, I claim: 75

1. An internally protected sheet metal receptacle formed of a plurality of interengaged blanks, and having a non-metallic layer of flexible fibrous material possessing a substantial degree of toughness and 80 strength cemented to and coextensive with the blanks of which the receptacle is formed, said layer being extended into and packing the joints where said blanks are interengaged in the completed receptacle. 85

2. An internally protected sheet metal receptacle formed of a plurality of interengaged blanks, and having a non-metallic layer of flexible fibrous material possessing a substantial degree of toughness and 90 strength cemented to and coextensive with the blanks of which the receptacle is formed, said layer being extended into and packing the joints where said blanks are interengaged in the completed receptacle, and a 95 protective coating which is inherently adherent to said lining and partly absorbed and reinforced thereby.

3. An internally protected sheet metal receptacle formed of a plurality of interengaged blanks, and having a non-metallic layer of flexible fibrous material possessing a substantial degree of toughness and strength cemented to and coextensive with the blanks of which the receptacle is formed, 100 said layer being extended into and packing the joints where said blanks are interengaged in the completed receptacle, a protective coating which is inherently adherent to said lining and partly absorbed and reinforced thereby, said coating being insoluble in alcohol and non-adherent to the metal of which the receptacle is constructed. 105

In testimony whereof I have affixed my signature, in presence of two witnesses.

WILLIAM A. SEXTON.
